METHOD FOR HANDLING FRESHLY PRINTED PAPER IN ROLL FORM

Walter K. Miller, La Grange, Ill., assignor to
Shellmar Products Company, Chicago, Ill., a
corporation of Delaware

Application May 19, 1930, Serial No. 453,635
Renewed April 28, 1934

2 Claims. (Cl. 101—420)

The invention relates to a method for handling freshly printed paper in roll form, such as "Cellophane", glassine and other papers that do not absorb ink to any appreciable extent, whereby such freshly printed paper may be dried in roll form.

Heretofore, so far as I am aware, it has been customary in the process of drying freshly printed paper of the type above described to dry the same in sheet form and this has necessitated the use of a great deal of valuable space in the printing establishment and considerable labor in the handling of the paper in connection with this drying process. The object of the present invention is to provide a method which permits the drying of the freshly printed paper in roll form so that the freshly printed paper, in roll form, can be readily handled and will occupy a small space while drying.

In accordance with the present method the freshly printed paper is rolled with a backing sheet provided with raised portions at intervals on the sheet where no printing occurs on the sheet, with the result that as the printed paper is rolled the freshly printed matter is spaced from the backing sheet and permitted to dry while the paper is in roll form.

The invention further consists in the several features hereinafter set forth and more particularly defined by claims at the conclusion hereof.

In the drawings Fig. 1 is a side elevation view of apparatus used in carrying out the method embodying the invention;

Fig. 2 is a detail sectional view through a part of the rolled sheet showing it flattened and taken along the line 2—2 of Fig. 3;

Fig. 3 is a plan view of a portion of the sheet that has been flattened from the roll to illustrate the method embodying the invention.

Referring to Fig. 1, the apparatus for carrying out the invention includes a frame 5 provided with a receiving roll 6 whose shaft 7 is journaled in suitable bearings 8 on the frame and carries a pulley 9 connected by a belt 10 to a pulley 11 on a shaft 12 driven by any suitable source of power, not shown, the belt being tensioned in known manner by a roller 13 mounted on a swinging frame 14 from a fixed support 15.

The freshly printed paper 16 is led from the printing machines over a guide roller 17 carried by brackets 18 on the frame 5 and down to the receiving roll 6 upon which it is wound. As the printed paper is being wound on this roll a backing sheet 19 from a supply roll 20 of the same is led from its supporting roll 21 over guide rollers

22, 23 and 24 down to the receiving roll 6 so that both the printed paper 16 and the backing sheet 19 are rolled together on the receiving roll, the guide rolls 24 and 17 being spaced apart so that a space 25 is provided between the paper and the backing sheet just before the two come together on the receiving roll. In this space I previously mount an air supply pipe or header 26 provided with a plurality of small openings 27, one of which is shown, said openings being spaced apart 5 so as to provide for a multiplicity of air jets being projected between the two sheets of the roll as they come together on the receiving roll.

Referring to Figs. 2 and 3, it will be noted that the backing sheet 19 is provided at spaced intervals with strips 28, these strips 28 facing the printed sheet 16 as the two sheets come together on the receiving roll and being located on the backing sheet at points spaced from the freshly printed matter 29 on the printed sheet 16. These 20 strips 28 by reason of their thickness provide elevations on the face of the main body of the backing strip 19 and are previously formed by securing strips of paper to the main body of the backing sheet 19 by suitable adhesive, though they 25 may be formed in other ways in order to provide raised portions on the backing sheet at spaced points in order to space the freshly printed material on the face of the sheet 16 away from the opposing face of the main body of the backing 30 sheet 19. The result is that when the two sheets are brought together and rolled on the receiving roll 6 that spaces 30 are provided between the printed sheet and the backing sheet at those 35 points where the freshly printed matter on the printed sheet occurs, with the result that an air space is provided which permits ready drying of the printed matter without danger of smearing the ink on to the backing sheet and ruining the printed matter and the printed sheet and the 40 backing sheet may thus be expeditiously rolled together as the printed matter comes from the printing machine.

In order to increase the effect of these air spaces where the printed matter occurs on the 45 sheet the air from the jets 27 is also directed into the spaces 30 between the sheets as the sheets come together for the purpose of bulging the sheets as they are rolled together as well as having some drying effect, with the result that the freshly 50 printed paper may be readily and expeditiously handled and dried in roll form.

The backing sheet 19 with the strips 28 may be formed in various ways but for the purpose of this application I have shown such sheet as 55

previously formed for use in connection with the printed paper.

I desire it to be understood that this invention is not to be limited to any particular form or arrangement of parts or to all the steps of the method except insofar as such limitations are included in the claims.

What I claim as my invention is:

1. The method which comprises printing a continuous web of paper along transversely spaced portions whereby the space between said portions is not provided with printing, and simultaneously rolling the freshly printed paper together with a continuous backing sheet provided

15 with longitudinally extending spaced projections

corresponding in position to the position of the unprinted portions of said web, whereby when rolled said printed portions alternate with said raised portions transversely of said roll.

2. The method which comprises printing a continuous web of material along transversely spaced portions, whereby to provide spaces between the printed portions which are not printed, and simultaneously rolling the freshly printed paper together with longitudinally extending bands corresponding in position to the position of the unprinted spaces of said web of material, whereby when rolled said printed portions alternate with said bands transversely of said roll.

WALTER K. MILLER. 15
